CAFETERIA COUNTER UNIT

Delmar D. Rhoads, 3230 S. Calhoun St.,
Fort Wayne, Ind.

Filed June 9, 1958, Ser. No. 51,238

Term of patent 14 years

(Cl. D80—2)

Figure 1 is a rear perspective view of a cafeteria counter unit showing by new design;

Figure 2 is a top view of the cafeteria counter unit illustrated in Figure 1;

Figure 3 is a rear elevational view of the cafeteria counter unit illustrated in Figure 1. The far end or side portion is substantially plain; and

Figure 4 is a fragmentary view of a corner of the top front of the cafeteria counter unit illustrated in Figure 1.

I claim:

The ornamental design for a cafeteria counter unit, substantially as shown and described.
